SHOE

Henry Lipton, Chicago, Ill., assignor to J. P. Smith
Shoe Company, Chicago, Ill., a corporation of
Illinois

Application April 27, 1953, Serial No. 24,693

Term of patent 14 years

(Cl. D7—7)

To all whom it may concern:

Be it known that I, Henry Lipton, a citizen of the United States of America, residing at city of Chicago, county of Cook, and State of Illinois, have invented a new, original, and ornamental Design for a Shoe, of which the following is a specification, reference being had to the accompanying drawing, forming a part thereof.

Figure 1 is a front perspective view of a shoe embodying my new design; and

Figure 2 is a rear perspective view thereof.

The dominant features of the design reside in the portions shown in full lines, the design being particularly characterized by the configuration of that portion of the shoe which is shown in full lines.

I claim:

The ornamental design for a shoe, as shown and described.
